SPINDLE STOP MOTION

William R. Gordon, Stonington, Conn., assignor
to The Atwood Machine Company, Stonington,
Conn., a corporation of New Jersey

Application December 27, 1938, Serial No. 247,764

5 Claims. (Cl. 57—80)

This invention relates to textile machines such as doubling and twisting machines and particularly to actuating means for a stop motion mechanism.

5 An object of the invention is to provide a simple and rugged operating mechanism for rapidly oscillating a pair of stop motion shafts on opposite sides of a machine on which are mounted the knock-off levers which, in the event of a 10 thread breaking or running out, will stop operation of the spindle for that thread.

Another object of the invention is to provide means to rotate an eccentric which will actuate a connecting rod one end of which fits over the 15 eccentric, the opposite end of the connecting rod being attached to a system of toggle levers to which a rocker shaft lever is attached.

And finally it is an object of the invention to mount the operating eccentric for the connecting 20 rod upon an eccentric bearing for its shaft so that by rotating this bearing a portion of a revolution the connecting rod and its eccentric will be moved to a position to disengage their driving member.

25 With the above and other objects in view, the invention may include the features of construction and operation set forth in the following specification and illustrated in the accompanying drawing.

30 In the accompanying drawing annexed hereto and forming a part of this specification, I have shown the invention embodied in a standard doubling and twisting machine but it will be understood that the invention can be otherwise embodied and that the drawing is not to be construed as defining or limiting the scope of the 35 invention, the claims appended to this specification being relied upon for that purpose.

In the drawing:

40 Fig. 1 is a fragmentary end elevation of a doubling and twisting machine showing the present invention applied thereto;

Fig. 2 is a plan view of some of the parts shown in Fig. 1;

45 Fig. 3 is a view of the mechanism forming the present invention taken from the left hand side of Fig. 1;

Fig. 4 is a detail view of some of the operative parts of the mechanism, and

50 Fig. 5 is a detail sectional view of part of the mechanism to render the mechanism inoperative, the section being taken on the plane of line 5—5 of Fig. 3.

In the above mentioned drawing there has 55 been shown but one embodiment of the invention

which is now deemed preferable, but it is to be understood that changes and modifications may be made within the scope of the appended claims without departing from the spirit of the invention.

Briefly, and in its broadest aspect, the invention may include the following principal parts: first, a rocker shaft on which are mounted stop motion actuators at spaced positions along the shaft; second, a lever or arm on said rocker shaft; 10 third, a pair of toggle links one end of one of these links being attached to the lever and the opposite end of the other link being pivotally attached to a fixed part of the machine; fourth, a connecting rod attached at one end to the joint 15 connecting the two links together; fifth, an eccentric to which the opposite end of said connecting rod is attached; sixth, a shaft mounting the eccentric and rotatable at constant speed; and seventh, means to move said shaft to dis- 20 engage its driving connections.

In textile machines such as doubling and twisting machines it is usual to provide means to stop operation at any spindle whenever a thread breaks or runs out. For that purpose the threads pass 25 over drop wires so that when a thread breaks or runs out the drop wire moves to a position to interpose the end of a member in the path of an actuator most usually mounted on a constantly oscillating shaft. This actuator and the 30 member engaged and moved thereby when a thread breaks release a latch and render the spindle inoperative by stopping its rotation. The present invention relates to the means for constantly oscillating a shaft to move the actuators 35 thereon into and out of positions to operate the latch means. As it is desirable to stop operation at a spindle promptly when a thread breaks means are provided for oscillating the actuator 40 shaft rapidly, smoothly and to a predetermined limited position. Furthermore, additional means are provided to stop oscillation of the actuator shaft whenever it is necessary to eliminate the stop motion action as when the machine is being initially started.

Referring more in detail to the figures of the drawing there is shown at 10 and 11 rocker shafts to which stop motion actuators 12 are attached. The oscillating shafts 10 and 11 extend longitudinally of the machine one on each side and 50 are suitably supported by means of aligned bearings in the machine frame members not shown. These actuators 12 spaced along the shafts 10 and 11 are oscillated back and forth adjacent drop wire controlled members 13 so that when a 55

thread breaks or runs out and a drop wire 14 falls back one end of a member 13 is interposed in the path of movement of an actuator 12. The effect of this is to release a latch 15 and 5 permit upward movement of a vertical shaft 16 to stop rotation and feeding movement at one of the spindles (not shown). As the above described mechanism is usual and standard for silk and rayon doubling and twisting machines it is not 10 thought that further description is necessary. It will be sufficient to state that the actuators 12 are constantly oscillated with their shafts 10 and 11 by the improved means forming the present invention and that they are rendered inoperative 15 by manually shifting a member of their operating means presently to be more fully described.

To oscillate the actuators 12 there is provided a driving shaft 16 having a sprocket wheel 17 thereon over which may run a driving chain 18 20 driven at suitable constant speed from any suitable means on the machine. Rotation of the sprocket wheel 17 rotates a gear 19 formed integrally therewith which meshes with a driven gear 20 on an intermediate shaft 21. Adjacent 25 the driven gear 20 and also secured to the shaft 21 is an eccentric 22 so that rotation of the driven gear 20 and intermediate shaft 21 will rotate the eccentric 22. Surrounding the eccentric 22 is the larger end of a connecting rod 23 30 the opposite or upper end of which is attached to the central joint between a pair of toggle links 24 and 25. One end of one of these links 25 is attached in fixed position to an end frame of the machine or to a bracket 9 secured thereto. The 35 opposite end of the second link 24 is attached to a short lever 26 secured to one of the rocker shafts 10. It will be seen from the above described construction that rotation of the eccentric 22 with its shaft 21 will move the lower end 40 of the connecting rod 23 in a circle and cause its upper end to move up and down to oscillate the links 24 and 25 above and below their central plane. This will cause oscillatory movement 45 of the short lever 26 and thus oscillating movement of the rocker shaft 10.

Each up and down stroke of the connecting rod 23 oscillates the shaft 10 to the right and left. The limiting position in one direction is 50 when the links 24 and 25 are in the same plane and in this limiting position the actuators 12 on shaft 10 are in position to operate the latch 15 whenever a drop wire 14 is down.

As there are spindles on opposite sides of the textile machines for which this invention is applicable the rocker shaft 10 has secured to it a lever 27. The rocker shaft 11 on the opposite side of the machine has a similar lever 28 and the two levers 27 and 28 are connected by a reach arm 29. With the levers 27 and 28 and reach 55 arm 29 connected as shown in Fig. 1 the stop motion actuators 12 are oscillated simultaneously toward and from the latch detents on opposite sides of the machine and are always brought to the same limiting position to actuate the detent 60 and release the latch lever when the links 24 and 25 are in their central or mid position. The oscillatory movements of the rocker shafts 10 and 11 depend upon the eccentric 22 the eccentricity of which relative to shaft 21 is sufficient 65 to give these shafts 10 and 21 sufficient amplitude of movement.

The shaft 21, on which is mounted the eccentric 22 for actuating the links 24 and 25, is supported within an eccentric bearing 30 rotatably 70 mounted in the bracket 9 secured to an end

frame of the machine. Bearing member 30 is provided with an arm 31 by means of which it may be rotated to move the axis of shaft 21 as indicated in Fig. 5. In one position of the eccentric bearing 30 the shaft 21 is held in a position to engage the teeth of gear 20 with those of the driving pinion 19. In the other position of the eccentric member 30 the shaft 21 is held in a position which separates gears 19 and 20 and therefore stops rotation of eccentric 22 and operation of the shafts 10 and 11. To retain the bearing member 30 in either of its positions a locking lever 32 is provided which in either position of the member 30 engages a detent or lug within a recess formed in the lever 32. 15

I claim as my invention:

1. A stop motion operating mechanism for textile machines comprising in combination, a rocker shaft, latch releasing actuators thereon, an arm on said shaft, a pair of toggle links hinged together, one end of one of said links being attached to said arm and the opposite end of the other link being pivoted to a fixed part of said machine, a connecting rod connected at one end to the central pivotal joint of said toggle links, and an eccentric engaging the opposite end of said connecting rod, whereby rotation of said eccentric will oscillate said links and said rocker shaft. 20

2. A stop motion operating mechanism for textile machines comprising in combination, a rocker shaft, latch releasing actuators thereon, an arm on said shaft, a pair of toggle links hinged together, one end of one of said links being attached to said arm and the opposite end of the other link being pivoted to a fixed part of said machine, a connecting rod connected at one end to the central pivotal joint of said toggle links, an eccentric engaging the opposite end of said connecting rod, whereby rotation of said eccentric will oscillate said links and said rocker shaft, and means to render said eccentric inoperative to oscillate said links and rocker shaft. 35

3. A stop motion operating mechanism for textile machines comprising in combination, a rocker shaft, stop motion actuators thereon, oscillating means for said rocker shaft including pivotally connected toggle links, oscillation of which oscillates said rocker shaft and actuators into and out of latch releasing position, an eccentric 40 connected to the central joint of said links whereby rotation of said eccentric oscillates said links and rocker shaft, and means to render said eccentric inoperative to oscillate said links and rocker shaft. 45

4. A stop motion operating mechanism for textile machines comprising in combination, a rocker shaft, latch releasing actuators thereon, an arm on said shaft, a pair of toggle links hinged together, one end of one of said links being attached to said arm and the opposite end of the other link being pivoted to a fixed part of said machine, a connecting rod connecting at one end to the central pivotal joint of said toggle links, an eccentric engaging the opposite end of 50 said connecting rod, whereby rotation of said eccentric will oscillate said links and said rocker shaft, a shaft supporting said eccentric, and an eccentric bearing for said last mentioned shaft, whereby said shaft may be moved to operative 55 and inoperative positions.

5. A stop motion operating mechanism for textile machines comprising in combination, a rocker shaft, latch releasing actuators thereon, an arm on said shaft, a pair of toggle links hinged 75

together, one end of one of said links being attached to said arm and the opposite end of the other link being pivoted to a fixed part of said machine, a connecting rod connected at one end to the central pivotal joint of said toggle links, an eccentric engaging the opposite end of said connecting rod, whereby rotation of said eccentric will oscillate said links and said rocker shaft,

a shaft supporting said eccentric, an eccentric bearing for said last mentioned shaft, whereby said shaft may be moved to operative and inoperative positions, and a latch to retain said last named shaft in its operative and inoperative positions.

5

WILLIAM R. GORDON.
